Primary Examiner—Brian N. Vinson**Attorney, Agent, or Firm**—Haugen and Nikolai**[57]****CLAIM**

The ornamental design for the hanger assembly for ice skates, as shown and described.

DESCRIPTION

FIG. 1 is a perspective view of my design for a hanger assembly for ice skates;

FIG. 2 is a front elevational view of my design;

FIG. 3 is a side elevational view of my design taken from the right side of the view of FIG. 1;

FIG. 4 is a side elevational view of my design taken from the left side of the view of FIG. 1;

FIG. 5 is a top plan view of my design; and,

FIG. 6 is a bottom plan view of my design.
